(57) **CLAIM**

What is claimed is the ornamental design for a multi-functional cosmetic compact, as shown and described.

DESCRIPTION

FIG. 1 is a bottom, front and left side perspective view of an embodiment of a new design for a multi-functional cosmetic compact wherein at least some of the walls are transparent walls;

FIG. 2 is a front elevation view of the compact;

FIG. 3 is a left side elevation view of the compact;

FIG. 4 is a rear elevation view of the compact;

FIG. 5 is an exploded view of the compact;

FIG. 6 is a top plan view of the compact; and,

FIG. 7 is a bottom plan view of the compact.
